ABSTRACT OF THE DISCLOSURE

A hair setting and styling device, an elongated body of generally tapered cylindrical configuration and curved to accommodate the shape of the head to which it is applied. A plurality of pairs of fingers fixed to and extending radially from the body, the pairs of fingers being spaced apart axially of the body and being in alignment, and each finger of each pair of fingers comprising two circumferentially spaced apart projecting sections, the fingers being extended into the hair to be curled.

This invention relates broadly to the art of hair setting and styling devices, and in its more specific aspects it relates to such a device provided with means projectible into the hair to be curled which means insures that the hair extends substantially vertically from the scalp for expediting the drying thereof in the desired position relative to the scalp, and the device is also of a character to prevent the usual voids between individual curlers which results from conventional truly cylindrical hair setting devices; and the nature and objects of the invention will be readily recognized and understood by those skilled in the arts to which it relates in the light of the following explanation and detailed description of the accompanying drawings illustrating what I at present believe to be preferred embodiments or mechanical expressions of my invention from among various other forms, arrangements, combinations and constructions, of which the invention is capable within the spirit and scope thereof.

Curling and setting devices of the general character in which I am interested and which are now in widespread use are of generally true cylindrical configuration and a plurality of such curlers are inserted at the proper positions relative to the scalp of the hair to be wound thereon with the axis of each curler being generally parallel with a plane extending through the nose and the back of the head. The plurality of such cylindrical curlers of the prior art are positioned about the head or scalp in spaced relation and a section of hair to be curled is wound about each curler, and, of course, any suitable means may be used for clamping the wound section of hair about each curler while such hair is drying.

The use of these conventional curlers, in the manner briefly described above, results, when the hair is unwound from each curler, in a void between each curl, and it is necessary to work on each curl in a way commonly called "teasing," or in other manners, so as to eliminate these undesirable voids.

A further significant disadvantage in the conventional curlers and setters which I have described, resides in the fact that the hair which extends from the scalp and about each curler, extends from the scalp in substantially tangential relation thereto, so that the time required for the hair to dry is substantially lengthened.

It has been one of my prime objects to overcome the above mentioned disadvantages, and others, which are inherent in conventional hair styling and setting devices. In accomplishing this purpose, I have provided a hair setting and styling device which eliminates completely

the voids between curls, insures that the hair which extends from the scalp and about a curling device extends substantially vertically with respect to the scalp so as to expedite the drying thereof. It will be appreciated that a device of the character which I have developed will obviate the necessity for teasing or doing any further substantial work on the curls in order to produce the desired hair styling effect. Thus, the use of my device will reduce the length of time now required for hair curling and styling and may well reduce the expense involved in such operations.

Another characteristic of my invention resides in the fact that the number of curling devices required for curling and styling a head of hair is reduced over the number now necessary and in general use.

My invention also embodies a unique structure which is adapted to enhance and facilitate the application of each device against the head and into operative position with respect to the hair.

I have also included a structure combined with my hair setting and styling device which assures the maintenance of the device in proper hair curling position.

The hair setting and styling device of this invention may be formed of plastic, is economical to produce, easy to use, and under normal use conditions will last for a substantial length of time.

My invention involves generally an elongated tapered cylindrical body from which a plurality of fingers extend. In the use of the device the fingers are extended from, for instance, the forehead into the hair to be curled, until the body is at the edge of the hair. The hair is brought up between and over the tops of the fingers in a direction toward and diagonally with respect to the body, and then is wound about the body at substantially a 45 degree angle toward the narrow end of the elongated tapered body. The hair is wound on the body and is maintained in position thereon by any suitable and conventional clamping or the like means.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

FIG. 1 is a front elevational view illustrating prior art conventional curlers in operative position curling the hair.

FIG. 2 is an end view of a prior art curler illustrating how the hair, which is wound therearound, extends substantially tangentially with respect to the scalp.

FIG. 3 is a top plan view of my hair setting and styling device.

FIG. 4 is a view illustrating the position of the hair setting and styling device with the fingers thereof inserted into the hair to be curled, but prior to the winding of the hair over the tops of the fingers and about the body of the device.

FIG. 5 is a view similar to FIG. 4, only illustrating the winding of the hair over the tops of the fingers and about the body of the device.

FIG. 6 is a view in front elevation illustrating the curlers of FIGS. 3-5 in operative position curling the hair at the front of the head and also disclosing a right and left curler placed in proper curling position at the sides of the head.

In the accompanying drawings, and particularly FIG. 1 thereof, I have illustrated a head of hair wound on the conventional curlers and in the manner which is now commonly in use. In this figure I have designated the two top curlers by the reference numerals 1 and 5, and the

two side curlers which are used on the left side of the head by the numerals 7 and 9, and those used on the right side of the head by the numerals 11 and 13. These curlers are customarily of true cylindrical configuration and operatively mounted with the hair wound therearound in the manner as disclosed in FIG. 1 of the drawings. It will be seen that each curler is positioned on the head in planes which are substantially parallel to a line extending from the nose to the rear of the head of the individual being operated upon. In this prior method of hair curling a section of hair 15 is wound about each curler in the manner disclosed in FIG. 1 and is then clamped to the curler in any suitable and conventional manner.

FIG. 2 of the drawings is an end view in elevation of one of the curlers with a section of hair 15 wound thereabout and it will be apparent from this view that in these prior art curlers and the method of their use and positioning on the head, the strands of hair which are wound about the curler and which extend as at 17 substantially tangentially with respect to the scalp 19, will be relatively slow in drying, which is, of course, one of the several disadvantages in these prior art constructions.

It is also a fact, as I shall point out hereinafter, that the strands of hair 17 which extend tangentially from the scalp below each curler produce voids between each curl which must be worked on and manipulated to produce the desired wave.

As I have pointed out above, undesirable voids are formed in the hair and between the curlers when the conventional curlers, as illustrated in FIG. 1, are used. These voids, as will be explained in detail hereinafter, do not occur when my curling device and method are used. Consideration of FIG. 1 clearly illustrates that a void 21 will occur between the top curlers 1 and 5, and this void, which is caused by a combination of the tangential extension of the hair relative to the scalp, and by the positioning of the curlers, must be worked and manipulated out of the curls after removal of the curlers in order to eliminate the void in the final wave of the hair. It will further be apparent that voids 23 and 24 will also be formed between the curlers 7 and 9 and 11 and 13, respectively, and that these must be gotten rid of by teasing and/or other working on the curls.

The hair setting and styling device of this invention comprises an elongated, tapered and curved body 25, which provides a styling surface and may be formed of plastic or any other suitable material which is designed particularly to withstand long usage. As will become clear as this description proceeds the hair is wound on this body in the curling operation. Due to the end to end tapered formation of the body 25, such body has an enlarged end 27 and an opposite end 29 which is smaller or narrower than the end 27. As will be apparent from the drawings, the taper from the large end 27 to the small end 29 is constant and gradual.

Fixed to and extending radially from the body, or styling surface 25, are a plurality of longitudinally spaced apart pairs of hair supporting and guiding fingers, which I have designated in their entirety by the numeral 31. The pairs of fingers are not only longitudinally spaced apart but are also longitudinally aligned, taking into consideration the curvature of the body 25. Each pair of fingers 31 comprises two circumferentially spaced apart fingers 33, these spaced apart fingers 33 being in circumferential alignment, and due to the circumferential spacing thereof a free area 35 is provided between the fingers 33. Consideration, particularly of FIG. 3 of the drawings, discloses that the curvature of the elongated tapered body 25 provides a longitudinally extending concavity or head engaging surface 37 in the body, and that the pairs of fingers 31 radially extend from the body 25 directly adjacent to but circumferentially removed from the body concavity 37.

The body 25 is provided at its smaller end 29 with a notch 37' therein, and at its other end with a projecting

lug or circumferentially grooved protuberance 39. The purpose of the notch and protuberance will be described hereinafter.

While in the drawings I have shown seven radially projecting pairs of hair supporting fingers 31, it is to be understood that a greater as lesser number may be used and the resulting structure will still fall within the spirit and scope of this invention. It is also to be appreciated that the relative sizes and spacing of the fingers may be varied to suit different types of hair and hair styling techniques.

It is also a significant factor in the success of my invention that the concavity 37 is so formed on the body 25, and is of such contour to facilitate the placement of the device against the forehead or other part of the head of the individual whose hair is being curled. Since the body 25 is applied to the forehead of the individual, in position extending in a plane substantially normal to a line extending from the nose to the back of the head, it will be evident that the proper application of the device to the head is facilitated by making the curvature producing the concavity 37 in more or less conformity to the curvature of the forehead of the person being worked upon.

In use, the body 25 with the radially projecting pairs of hair supporting fingers 31, is applied to the forehead with the concavity 37 in contact therewith and generally conforming to the curvature of the forehead. The body 25 is applied to the forehead in position thereagainst extending across the forehead or, as stated above, in a plane substantially normal to a line extending from the nose to the back of the head, and the device is positioned with the body 25 thereof disposed as described so that the hair supporting fingers 31 extend into the hair, as clearly illustrated in FIG. 4 of the drawings. In this figure the body 25 is applied to the forehead in the manner as explained and with the fingers 31 projecting rearwardly into the hair which in this figure I have designated by the numeral 39'. The body is moved up the forehead to the edge of the hair line so that the fingers 31 project substantially their entire length into the hair. With the device so positioned the hair 39' is brought up between each pair of fingers 31 so that it extends from the scalp in substantially perpendicular relation thereto instead of being tangentially related thereto, as in the prior art, and as particularly illustrated in FIG. 2.

When the hair is positioned in this substantially perpendicular relationship relative to the scalp and extends upwardly between the pairs of fingers as disclosed in FIG. 4 of the drawings, it is then brought over the tops 41 of the uppermost fingers 33 of the pairs of fingers, being pulled or guided in a direction toward the small or narrow end 29 of the body 25, as particularly shown in FIG. 5 of the drawings. With the hair extending over the tops 41 of the particular fingers 33 and extending thereover in a direction towards the small end of the body, it will be understood that each strand of hair extends from the scalp to the tops of the fingers in substantially perpendicular relation with respect to the scalp. When the hair has been so arranged and positioned it is then wound about the body 25 at substantially a 45 degree angle toward the smaller and narrow end of the elongated, tapered and curved body 25, as is clearly illustrated in FIG. 5 of the drawings. When the hair has been wound as described, it is then clamped in wound position on the body 25 by means of any suitable and conventional clamping means 43 which is fixed to the protuberance 39 and extends over and under the body 25 and through the notch 37 as is shown particularly in FIG. 5 of the drawings.

As I have stated the body 25 provides a styling surface for the curls and this provides an excellent means for finalizing the depth of the curl desired so that it is not necessary with the use of my devices to have equal size curls as are provided by the prior art. This favorable feature will be understood clearly by one skilled in the art since

the diameter of the bodies may be varied to provide curls of different sizes, and such variation of the size of the bodies may be done without departing from the spirit and scope of this apparatus and the method of practicing the hair curling and styling.

With respect to the fingers these are shown as being at least of a length equal to the depth of the body portion from which the finger extends, however it is within my contemplation that they may be of any length from a stub to as long as is necessary to accommodate the operator's skill in use.

In FIG. 6 of the drawings I have illustrated the application of the curlers, not only to the top of the head but also to the sides of the head to set and curl the hair at both sides of the head. I have designated the hair setting and curling device which is used on the left side of the head generally by the numeral 45 and I have designated in its entirety the hair setting and curling device for the right side of the head by the numeral 45'. Each of the hair setting and curling devices 45 and 45' includes the body member or styling surface 25, the same arrangement of fingers 31 as has already been described. It will be understood that in the hair setting and curling devices 45 and 45' the fingers project from each body adjacent to but circumferentially removed from the concavity 37, it being apparent, in order to have the fingers 31 on the hair setting and curling devices 45 and 45' extend rearwardly into the hair that the device for one side of the head would have the fingers project from one surface of the body while the fingers of the device for the other side of the head will project from the opposite surface of the body. It is to be understood, and is clear from the drawings, that the bodies 45 and 45' are of elongated, tapering and curved configuration, however the degree of curvature may be varied in order to conform to the curvature at the side of the head, and it is also to be appreciated that it is within my contemplation to eliminate the curved configuration of these side head curlers for certain applications thereof.

When the hair has been wound as described in connection with FIG. 6 of the drawings the same procedure is followed as has been explained in connection with the prior figures. For it is then clamped in wound position on each body 25 by means of any suitable and conventional clamping means 43 which is fixed to the protuberance 39 on each body and extends over and under each body 25 and through each notch 37.

In the use of these curlers for the sides of the head, the curler 45 is positioned as shown in FIG. 6 with the fingers extending substantially horizontally from the front to the back of the head, and the hair is pulled from the scalp outwardly and through the fingers and then is guided on and over the tops 41 of the fingers 33, and then is wound about the body 25 in generally the same manner as has been described in connection with the curler for use on the forehead or top of the head. The right hand curler 45' is placed in position on the right side of the head with the fingers 31 extending substantially horizontally, or from front to rear of the head, and the left hand curler 45 is placed in position on the left side of the head with the fingers 31 extending substantially horizontally, or from front to rear of the head. It will further be appreciated that the right and left hand configurations of curlers 45 and 45' will be placed in successive positions from the front of the head to the back of the head, the curved axis of each series of curlers being in successive vertical planes parallel to the plane of the face.

In the arrangement of hair on and extending over the tops of the fingers and about the body, it is desirable to thread a small amount of hair through the area 35 between some or all of the fingers 33, as this will help to keep the curler body fitted more securely or snugly to the head. It also should be pointed out with respect to the curler which is used for the forehead or the top of the

head that some of the hair may also be threaded, in this instance, through the areas 35.

It is to be recognized that one, from among many, of the desirable characteristics of my curler having the fingers extending from the body thereof, is to permit the hair behind the main body to dry substantially perpendicular to the scalp and to eliminate the necessity of having to use and apply another curler directly behind the curler of this invention. This would be necessary if the curling device of this invention was not provided with the hair supporting fingers. It will be obvious that there are many disadvantages inherent in having to use a further curler.

It is to be recognized also that a previous hairdo from the day before having waves combed in that are suitable to my invention can be preserved by inserting my curler into said waves and secured with a hair net as for sleeping. The curvature of my invention and the support gained from the fingers will give support to a large area against the side of the head which will serve as a cushion and not disturb the waves being preserved for longer life of the hair style.

I claim:

1. A hair setting and styling device, comprising a substantially rigid elongated, generally cylindrical tapered body, providing a hair styling surface, hair supporting and guiding means fixed to and radially projecting from said body and relatively immovable with respect thereto and adapted to be inserted in the hair to cause it to extend substantially perpendicularly from the scalp prior to being wound on and pressed against said body, said hair supporting and guiding means comprising two circumferentially spaced apart longitudinally extending rows of rigid fingers, the fingers in each row being longitudinally spaced apart and in curved alignment, and the circumferentially adjacent fingers being in circumferential alignment, and means on said body for clamping the hair in wound position thereon.

2. A hair setting and styling device comprising an elongated generally cylindrical tapered body, providing a hair styling surface, hair supporting and guiding means fixed to and radially projecting from said body and adapted to be inserted in the hair to cause it to extend substantially perpendicularly from the scalp prior to being wound on and pressed against said body, and said body is curved providing a concavity in said body and said hair supporting and guiding means project from said body adjacent to but circumferentially removed from said concavity, and means on said body for clamping the hair in wound position thereon.

3. A hair setting and styling device in accordance with claim 2, wherein the upper edge of each finger which is remote from the concavity provides a hair supporting surface.

4. A hair setting and styling device in accordance with claim 2, wherein said fingers are arranged in pairs and the fingers of each pair are circumferentially spaced apart and in alignment, and the edge of one finger of each of said pairs of fingers which is remote from said concavity provides a hair supporting surface, and the edge of the other finger of each of said pairs of fingers which is remote from said concavity provides a further hair supporting surface.

5. A method of hair setting and styling, comprising those steps of inserting into the hair a plurality of hair supporting and guiding means which are fixed to and extend from a generally cylindrical body, providing a hair styling body, threading the hair between said plurality of hair supporting and guiding means in position extending substantially vertical with respect to the scalp, then guiding the free hair beyond those portions of the hair which extend between the hair supporting and guiding means over the edges of said supporting and guiding means in diagonal relationship with said generally cylindrical body and then winding said free hair around and pressing it against said generally cylindrical body in a

3,507,291

7

direction towards one end thereof, and clamping said wound and pressed hair to said generally cylindrical body.
